CLAIM

The ornamental design for an electrical charger, as shown and described.

DESCRIPTION

1. Electrical charger

1.1 : Top

1.2 : Front

1.3 : Back

1.4 : Left

1.5 : Right

1.6 : Bottom

1.7 : Perspective view top left

1.8 : Perspective view bottom right

The characteristic features of the design lie in the shape of the electrical charger as shown. The parts shown by means of broken lines in the reproductions are not part of the claimed design. The parallel thin lines and the radial thin lines in the representation represent contours only and do not illustrate an ornamentation or decoration on the surface of the product.
